UNITED STATES PATENT OFFICE.

DANIEL J. GILCHRIST, OF BERGEN POINT, NEW JERSEY.

MACHINE FOR RAISING PHOSPHATE ROCK.

SPECIFICATION forming part of Letters Patent No. 352,311, dated November 9, 1886.

Application filed March 5, 1886. Serial No. 194,170. (No model.)

To all whom it may concern:

Be it known that I, DANIEL J. GILCHRIST, of Bergen Point, Hudson county, State of New Jersey, have invented certain new and useful 5 Improvements in Machines for Raising Phosphate Rock, of which the following is a specification.

The object of my invention is to provide a new and improved machine for loosening the 10 phosphate rock on the beds of rivers and raising the loosened rock to the surface, which machine is simple in construction, strong, and effective in use.

The invention consists of a scow or other 15 suitable floating vessel, with inclined frames hanging at the sides and carrying bucket-chains, which frames are united at the front by a shaft, on which blades for loosening the rock are mounted, said frames being connected 20 with a suitable hoisting device for raising them. At the rear end of the scow an endless-chain bucket elevator is provided, which has the entire width of the scow and serves for raising the greater portion of the rock loos- 25 ened by the blades on the shaft at the front of the scow, all as will be fully described and set forth hereinafter, and pointed out in the claims.

In the accompanying drawings, Figure 1 is 30 a side view of my improved machine for raising phosphate rock, parts being broken out and others in section. Fig. 2 is a plan view of the same. Fig. 3 is a cross-sectional view of the front transverse shaft for loosening the 35 rock, and the blades on the same. Fig. 4 is a front view of part of the same, showing the blades. Fig. 5 is a top view of one of the buckets of the side elevators. Fig. 6 is a longitudinal sectional elevation of the same. Fig. 40 7 is a view of the open end. Fig. 8 is a cross-sectional view of one of the buckets of the rear bucket-chain and a side view of the pentagon pulley over which the chain passes. Fig. 9 is a plan view of part of a bucket on the chain. 45 Similar letters of reference indicate corresponding parts.

On each side of the scow or float A a heavy metal frame, B, is hung in such a manner that they are inclined downward and toward the 50 front, and the lower end of each frame can be raised or lowered, so that the frames have any

desired inclination. In the lower ends of said frames B a shaft, C, is journaled, which extends from one side of the scow to the other, at and below the front of the scow, and said shaft 55 is provided with two opposite longitudinal grooves, C', for receiving the teeth D', formed on the rear ends of cutting-blades D, having semicircular recesses to adapt them to fit on the shaft C. The prongs of the blades D may 60 be shaped as shown in Fig. 3, or have any other suitable shape, but in all cases should have a point and a tapered or knife edge, as shown in Fig. 4. Each blade D is provided in its outer edge with an offset or shoulder, 65 D², and in the edge above the prong D' with a recess, D³. Stirrups E are passed over the blades in such a manner that the cross-piece of the stirrup E rests against the offset or shoulder D², and the ends of the shanks of said stirrups are at the notch D³ of the opposite blade. A key, E', is then driven through the apertures in the ends of the shanks of the stirrups, the inner edge of said key passing into a notch, 70 D³, of one blade, the prongs D' of the blades 75 being placed into the grooves C'. The blades D are fastened to the shaft in pairs, as shown in Figs. 3 and 4. The prongs of each pair project in opposite directions, and the direction in which the prongs of the successive pairs of 80 blades project being alternately at right angles to each other, as shown in the ground plan, Fig. 2. The blades can be fastened or unfastened very easily and rapidly, and no bolts, screws, or like fastening devices are used. 85

Within the lower end of each frame B a polygonal wheel, F, (shown in dotted lines in Fig. 1,) is mounted on each end of the shaft C, and over said wheel or wheels F an endless link-chain, G, passes within each frame B, the 90 upper end of each link passing over a like polygonal wheel, F', mounted within the upper end of each frame B on a transverse shaft, H, which is rotated by means of one or two steam-engines, I, the steam for which is furnished by one or more steam boilers, I', adjacent to said engines. On each alternate link of the chain G a bucket, J, is fastened, on the outer side of which a series of prongs, J', are fastened at the open end. Said prongs J' are 100 forked, and the outer side of the bucket is inserted between the shanks of the prongs, and

rivets are passed through said shanks and the outer sides of the buckets, as shown in Figs. 6 and 7.

The lower ends of the frames B are connected 5 with cables or chains K, passed over pulleys K' and secured to a drum, K², of an engine at the front end of the scow. On an upright frame, T, on the rear end of the scow, which frame is suitably braced and stiffened, a frame, 10 M, is pivoted, which can be inclined downward and from the rear end of the scow. Said frame M consists of side pieces and two center pieces, as shown in Fig. 2; or it may consist of a greater number of center pieces, as 15 may be desired. A chain, N, or cable is connected to the frame M at its outer end, passes over suitable pulleys, L, and is connected with a drum of an engine, W, whereby the frame M can be raised or lowered.

20 An endless link-chain, O, is provided at each side of the frame M and at the middle, said chain passing over polygonal wheels or drums O', mounted on the upper and lower ends of the frame M, as in ordinary bucket-elevators.

25 On the links of the chain O buckets P are fastened, which have an approximately U-shaped cross-section, and extend from the sides to the center piece of the frame M, or, if desired, may be extended entirely across the frame M. On 30 the outer surface of each bucket P a series of sharp-pointed prongs, Q, are bolted or riveted, the ends of which project beyond the edges of the buckets. The engine W revolves the shaft carrying the upper polygonal pulleys 35 or wheels, O', on the upper end of the frame M.

On the lower end of the frame M a guard or scoop, S, is provided, which extends the entire width of the same, or from each end to the middle, as shown in Fig. 2, and which serves 40 to scoop up and gather the loosened pieces of phosphate rock.

The operation is as follows: While the scow is being towed to the place where the phosphate rock is to be raised the frames B and 45 M are raised, so as to be out of the water. When the desired place is reached, the front ends of the frames B are lowered until the prongs on the shaft C are on the bed of the river. The frame M is also lowered until its 50 guard S at the lower end also rests on the bed of the river. The shaft H is then revolved by the engines I I', whereby the buckets below the frames B are moved down and the buckets above the frame are moved upward, whereby 55 the shaft C is revolved in the direction of the arrow b', Fig. 1, the prongs of the blades D cutting into the rocks in the bed of the river and loosening and disintegrating the same. The loosened portions of the rocks at the sides 60 of the scow are raised by the elevator-buckets. The scow is slowly drawn forward in the direction of the arrow a', and the pieces of rock that have been loosened by the prongs of the blades of the shaft C are guided by the guard 65 S and are lifted by the buckets P of the frame

M and are deposited on the deck of the scow. The elevator-buckets of the rear frame, M, pick up the rock that has passed between the front frames, B.

The machine can be passed over the same 70 part of the river a number of times successively, the depth of the river being gradually increased.

Having thus described my invention, I claim as new and desire to secure by Letters Patent— 75

1. A machine for raising phosphate rock, consisting of a scow or float, a shaft suspended in front of and below the bottom of the scow, which shaft is provided with blades, a bucket-elevator at the rear end of the float and working entirely clear of the same, whereby the width of the elevator may be equal to that of the scow, and driving mechanism for operating the bucket-elevator, and the shaft carrying the blades, substantially as shown and described. 85

2. A machine for raising phosphate rock, consisting of a scow or float provided at each side with a swinging endless bucket-elevator frame, said frames having their lower ends at 90 the front part of the vessel connected by a shaft carrying blades, and with a bucket-elevator frame at the rear end of the vessel, the width of said rear elevator-frame being equal to the width of the vessel, substantially as 95 shown and described.

3. In a machine for raising phosphate rock, the combination, with a scow, of an inclined frame at each side, bucket-chains on the inclined frames, a shaft provided with blades 100 uniting said side frames at the front end of the vessel, a bucket-elevator chain at the rear end of the vessel, and separate engines for imparting motion to said bucket-chains at the front and rear parts of the vessel, substantially 105 as shown and described.

4. The combination, with a shaft, of blades having curved recesses to adapt them to fit on the shaft, and prongs which can be passed into recesses in the shaft, and of stirrups passed 110 over the blades for the purpose of holding them on the shaft, substantially as shown and described.

5. The combination, with the shaft C, having the longitudinal grooves C', of the blades D, 115 having the prongs D', which can be passed into the grooves C', the shoulders or offsets D'', the notches D'', and of the stirrups E, placed over the blades and having their shoulders resting against the cross-piece E², and the 120 keys E', passed through apertures in the shanks of the stirrups, substantially as shown and described.

In testimony that I claim the foregoing as my invention I have signed my name in presence of two subscribing witnesses. 125

DANIEL J. GILCHRIST.
